United States Patent Office

Des. 184,330
Patented Feb. 3, 1959

184,330

PORTABLE SHELTER

Donald F. Arbuckle, Canton, and Richard W. King, Massillon, Ohio; said King assignor to said Arbuckle

Application May 5, 1958, Serial No. 50,758

Term of patent 14 years

(Cl. D13—1)

Fig. 1 is a perspective view of a portable shelter illustrating our new design;

Fig. 2 is a front elevation of the same; and

Fig. 3 is a side elevation of the same.

We claim:

The ornamental design for a portable shelter, substantially as shown.
